SHEET-STOCK AXIALLY DRIVEN
PERMANENT FASTENER

Edwin A. Miller, New Haven, Conn.

Application July 14, 1941, Serial No. 402,285

4 Claims. (Cl. 85—11)

This invention relates to permanent securing means for axially driven fasteners within channels or bores provided therefor, and more particularly to such fasteners produced from sheet-stock.

The objects of the invention are to provide a permanent securing means for sheet-stock fasteners adapted to be driven within passages provided therefor in fiber, metal or other stock that is less hard than the fastening device; to provide for a sheet-stock fastener integral resilient portions having cutting shoulders rearwardly extending beyond the inner wall surface of the path of the driven fastener; and to provide for such a fastener a shank of such form adapted to fit the particular passage prepared therefor.

With reference to the accompanying drawing, the Figure 1 is an upright face view of the preferred form of the device; the Figure 2 is an upright side view; the Figure 3 is a cross-section of the device on the line 3—3 of the Figure 2, the section of the device being illustrated in connection with the inner wall-surface of the passage prepared therefor; the Figure 4 is an upright face view of a modified form of device; the Figure 5 is an upright side view of the device illustrated by the next previous figure; the Figure 6 is a cross-section of the modified device on the line 6—6 of the Figure 5, the section of the device being illustrated in connection with the inner wall-surface of the passage prepared therefor; the Figure 7 is an upright perspective view of a further modified form of device; the Figure 8 is an upright side view of said further modified form; the Figure 9 is a cross-section of the device on the line 9—9 of the Figure 8, the section being illustrated in connection with inner wall-surface of the bore prepared therefor; and the Figure 10 is a diagrammatic sketch of detail.

With more particular reference to the accompanying drawing the numeral 1 designates the sheet-metal body of the preferred form of the device illustrated by the Figures 1, 2 and 3. The sheet-metal body 1 is provided in strips of any desired width and length and the side edges 2 and 3 of both extremities are transversely cut at intervals, as at 4, to provide at alternate cut sections a series of fins 5 along said edges 2 and 3. Following the cutting process, or simultaneously therewith, the fins 5 are formed and twisted up out of the plane of the body strip 1 and out of alignment with said edges 2 and 3, each fin 5 being divergently directed away from the free ends of the strip 1, as best illustrated by the Figure 2, 55

and said twisting formation providing for each fin 5 a cutting corner shoulder 6 projecting slightly beyond its respective edge 2 or 3. The fins 5 being formed as aforesaid, the intermediate portion of the body strip 1 is looped upon itself to provide the transverse head 7 with the closely parallelly positioned extremities brought into axially depending association, one with the other, to together provide the shank 8 of the device having the free end 9 of less width than that of the body strip 1.

The socket or passage, designated by the inner wall-surface 10, for the driven insertion of the shank 8 of the device being determined and prepared, the free end 9 of the shank 8 is initially placed within the entrance to the passage until the pair of fins 5 adjacent said free end 9 obstruct the further entrance by reason of their cutting corner shoulders 6 projecting beyond the path of the shank 8 and the inner wall-surface 10 of the passage, as illustrated by the Figure 3. Sufficient force then applied to the head 7 of the device will drive and crowd the resilient fins 5 from their normal positions, with regard to the inner wall-surface 10, so that they, each pair in succession, are made to enter the passage until the shank 8 is fully driven home, the tension of resiliency causing each shoulder 8 to bear its cutting corner 6 against the wall-surface 10. Upon subsequent separating strain, such strain will be met and resisted by said cutting shoulders 6 digging into the inner wall-surface 10 of the passage and thereby establishing an opposing abrupt shoulder 11 in the inner wall-surface 10 in locking engagement with each of the shoulders 6 of the fins 5, thereby permanently securing the device within the passage prepared therefor, the opposing abrupt shoulders 6 and 11 being shown diagrammatically by the Figure 10.

The modified device, illustrated by the Figures 4, 5 and 6, is quite similar to that of the preferred form, excepting that its head 1A and shank 8A are formed from a single thickness of a sheet-metal body 1A of which the head 1A is formed by axially cutting into the end of the metal body strip 1A with two equally spaced cuts and bending the two outer end portions 1B and 1C in one right angled direction and the center cut portion 1D in the opposite direction to altogether provide the head 1A in a transverse relation to the vertical shank 8A. Both edges 2A and 3A of the shank 8A are cut transversely at equal intervals and the cut sections are similarly formed as in the preferred form, excepting that, in form, the successive cut sections are twisted

in alternate directions out of the plane of the sheet-metal body 1A and out of alignment with the edges 2A or 3A and divergently directed toward the head 1A to provide the fins 5A. The manner of driving and securing the device within the inner wall-surface 10A of the passage prepared therefor is identical with that of the preferred form.

The further modified form of the device, illustrated by the Figures 7, 8 and 9, is intended primarily for a bore into which the shank of the device is driven. The sheet-metal strip form of the body 1 and the head 1 is identical with that of the preferred form. The shank of this modified form, while it employs the parallelly associated sheet-metal shank portions, as in the preferred form, is provided with only two fins 5B at the free end of said shank portions, each bent divergently upward and outward. The manner of driving and securing this modified form of the device within the bore provided therefor is very similar to that of the preceding forms, excepting that, as illustrated by the Figure 9, the corners of the upturned fins 5B provide the cutting shoulders 6C that, as the device is driven within the inner wall-surface 10B of the bore, the resilient fins 5B are made to yield inwardly to admit the shank, and upon separating strain the cutting shoulders 6C dig into the inner wall-surface 10B thereby providing abrupt shoulders in said wall-surface that oppose the cutting shoulders 6C of the fins 5B.

I claim:

1. A permanent driven fastening means comprising a folded strip of sheet-metal providing a closely associated double thickness of a shank; a head integrally formed at the folded extremity of the shank; a reduced width of the strip at the free ends of the shank; resilient fins integrally formed within the side edges of both shank portions by means of cuts at intervals therein perpendicular to the said side edges and a portion of each alternate cut sections thereof so twisted outwardly from the plane of its shank portion that its base and one free corner remain in shank alignment; a cutting corner shoulder with which each fin is provided, said shoulders being the outwardly twisted corner portion of said alternate sections directed divergently toward said head and normally extending beyond the inner wall-surface of a socket into which the fastening means is to be driven.

2. A permanent driven fastening means comprising a folded strip of sheet-metal providing a closely associated double thickness of a shank; a reduced width of the strip at the free ends of the shank; resilient fins integrally formed within the side edges of both shank portions by means of cuts at intervals therein perpendicular to the side edges and a portion of each alternate cut sections thereof so twisted outwardly from the plane of its shank portion that its base and one free corner remain in shank alignment; a cutting corner shoulder with which each fin is provided, said shoulders being the outwardly twisted corner portion of said alternate sections directed divergently away from the reduced ends of the shank and normally extending beyond the inner wall-surface of a socket into which the fastening means is to be driven.

3. A permanent driven fastening means comprising a folded strip of sheet-metal providing a closely associated double thickness of a shank; a head integrally formed at the folded extremity of the shank; resilient fins integrally formed within the side edges of both shank portions by means of cuts at intervals therein perpendicular to the said side edges and a portion of each alternate cut sections thereof so twisted outwardly from the plane of its shank portion that its base and one free corner remain in shank alignment; a cutting shoulder with which each fin is provided, said shoulders being the outwardly twisted corner portion of said alternate sections directed divergently toward said head and normally extending beyond the inner wall-surface of a socket into which the fastening means is to be driven.

4. A permanent driven fastening means comprising a folded strip of sheet-metal providing a closely associated double thickness of a shank; resilient fins integrally formed within the side edges of both shank portions by means of cuts at intervals therein perpendicular to the said side edges and a portion of each alternate cut sections thereof so twisted outwardly from the plane of its shank portion that its base and one free corner remain in shank alignment; a cutting shoulder with which each fin is provided, said shoulders being the outwardly twisted corner portion of said alternate sections and extending beyond the inner wall-surface of a socket into which the fastening means is to be driven.

EDWIN A. MILLER.
